Patented July 28, 1925.

UNITED STATES PATENT OFFICE.

CHARLES GARDNER, OF AKRON, OHIO, ASSIGNOR TO THE MILLER RUBBER COMPANY,
OF AKRON, OHIO, A CORPORATION OF OHIO.

WASHER-PLACING APPARATUS.

Application filed April 24, 1924. Serial No. 708,825.

To all whom it may concern:

Be it known that I, CHARLES GARDNER, a citizen of the United States, and resident of Akron, in the county of Summit and State 5 of Ohio, have invented certain new and useful Improvements in Washer-Placing Apparatus, of which the following is a specification.

My present invention relates to improvements in devices for placing washers on the pins of heel molds preparatory to their being incorporated or embedded in the rubber heel or heels during the molding thereof.

The invention aims to provide a simple and economical form of apparatus by which the washers may be expeditiously handled and accurately placed on the pins, and the said invention comprises the novel features of construction and arrangement and combination of parts hereinafter described and particularly defined by the claims appended hereto.

An embodiment of my invention is illustrated in the accompanying drawings in 25 which:—

Figure 1 is a longitudinal sectional view of my combined washer-segregating and delivering plates or members.

Fig. 2 is a similar view with the washer-expelling or projecting means applied thereto, and

Fig. 3 is a like view showing the parts of Fig. 1 applied to a heel mold and with the washers projected onto the mold pins.

Fig. 4 is a detail view.

Referring by reference characters to this drawing, the numeral 1 designates the lower section of the heel mold having the customary upstanding washer-holding pins 1^a to receive and hold the washers 2, which, as shown, are of somewhat dished form, or provided with an annular deflected portion adjacent the washer opening.

These mold sections are provided with 45 dowel pins 3 which serve to accurately align the washer-placing device, as hereinafter described.

It is, of course, obvious that my invention may be embodied in a device for applying washers to a mold having a single heel cavity, or a plurality of cavities, the latter being shown by way of example.

The numeral 4 designates what I may term a washer-delivering plate or member, 55 cooperating with which is a washer-seg-

regating plate 5 slidably superposed thereon. Plate 4 has groups of openings 4^a positioned to correspond to the groups of pins 1^a, and plate 5, groups of similarly placed openings 5^a, these openings being of a size adapted to receive and permit free passage of the washers.

The edges of the openings 5^a are beveled or countersunk, as indicated at 5^b for a purpose which will hereinafter appear.

Plate 5 is held slidably superposed on plate 4 in determined relation thereto by suitable means such as dowels 5^c engaging elongated openings 4^c in the plate 4, the relation of the parts being such that at the limit of relative movement in one direction, the holes 4^a are out of alignment with holes 5^a, the latter being closed at the bottom by intact portions of the plate 4 which converts the openings 5^a into washer-receiving recesses. The ends of the dowels 5^c are threaded and provided with nuts ^c for removably holding the plates together.

When the parts are in such position, as shown in Fig. 1, they are adapted to be used as a washer-segregating device, as, if a miscellaneous lot of washers is placed or dumped on plate 5 and the latter shaken, the washers will slide about over the surface of the plate and those which have their convex side uppermost will lodge in the washer-receiving recesses, while those which are inverted, or have their convex side down, will slide across the washer seats by reason of the beveled sides 5^b, hereinbefore referred to.

After all the washer-receiving recesses or seats, are filled, the surplus washers may be removed by tipping the plate to allow them to slide off into any suitable receiver. The assembled plates 4 and 5 carrying the washers seated as above described, can be applied to the mold, being properly aligned therewith by the mold dowels 3 engaging openings 4^d and 5^d in the plates 4 and 5 respectively. If, now, the plate 4 is moved to the right, (Fig. 1) to the limit of movement allowed by the elongation of holes 4^e and 4^d, the openings 4^a will be brought into alignment with holes 5^a and the washers will be permitted to drop through onto the pins, after which the plate assembly is lifted off, leaving the washers properly positioned on the pins.

The device as above described operates very satisfactorily with heel molds for mak-

ing plain or flat heels, where the pins are all in the same horizontal plane.

In the manufacture of curved heel lifts, such as shown in the I. T. S. heel, the upper ends of the pins are not in the same plane, as shown in Fig. 3, and hence the openings 4^a cannot be closely juxtaposed to all the pins, and a space is left above some of the pins which permits the washer to tip as it is released by the sliding action and hence fail sometimes to engage the mold pin. To avoid this objection, I provide means for holding the washers in place in the washer seats until the latter are fully uncovered and then forcibly ejecting them, whereby tipping of the washers is prevented.

Such means preferably takes the form of a carrying member 6 having spring pressed plungers 7 provided with concave lower ends 7^a and mold pin receiving recesses 7^b. These plungers are grouped to correspond to the openings 5^a and means are provided by which member 6 may be properly held relative to plate 5, such means conveniently taking the form of shouldered dowels 8 having their reduced upper ends 8^a engaging openings 6^a in member 6.

The plungers 7 are slidably guided in guides or openings 6^b of member 6 and held against dislodgment therefrom by cotter pins 7^c, and they are provided with annular ribs or shoulders 7^d between which and the lower surface of plate 6 compression springs 9 are confined. In using this ejecting means, plate 6 is superposed over plate 5 and aligned therewith by dowels 8 while the washers are held in the seats, plate 6 being pressed towards plate 5 to compress the springs, and held in such position by means of catches 10 engaging detents or keepers 11 carried by upturned flanges 4^x of plate 5. If now the assembly is applied to a heel mold and plate 4 is moved to align the openings 4^a and 5^a, the pressure of the plungers will hold the washers against the surface of plate 4 by reason of their annular engagement, until the openings are perfectly aligned, and thereafter the washers will be projected upon the pins without danger of tipping or deflection, as shown in Fig. 3,

it being understood that the plungers act more rapidly than the force of gravity.

Having thus described my invention, what I claim is:—

1. A washer-placing device comprising a pair of plate-like members slidably juxtaposed and having each a group of washer-receiving openings adapted to be aligned by a relative sliding movement of the members, means for properly registering such members with a heel mold, and means for forcibly expelling the washers when the openings in such members are brought into alignment. 55

2. A washer-placing device comprising a pair of plate-like members slidably juxtaposed and having each a group of washer-receiving openings adapted to be aligned by a relative sliding movement of the members, and means for properly registering such members with a heel mold, said means comprising aligning dowel openings in said members, the openings in the lower member being elongated. 60

3. A washer-placing device comprising a pair of plate-like members slidably juxtaposed and having each a group of washer-receiving openings adapted to be aligned by a relative sliding movement of the members, a carrier member adapted to be removably secured over the upper of said members, and a group of spring plungers supported by said carrier member, and positioned to correspond to the openings in said upper member. 75

4. A washer-placing device comprising a pair of plate-like members slidably juxtaposed and having each a group of washer-receiving openings adapted to be aligned by a relative sliding movement of the members, a carrier member adapted to be removably secured over the upper of said members, and a group of spring plungers supported by said carrier member, and positioned to correspond to the openings in said upper member, said plungers having annular washer-contact portions at their lower ends. 80

In testimony whereof, I affix my signature.

CHARLES GARDNER.
